INVENTOR.

T. SMITH, Jr.

United States Patent Office.

THOMAS SMITH, JR., OF BOSTON, MASSACHUSETTS.

Letters Patent No. 101,672, dated April 5, 1870.

IMPROVEMENT IN TEAPOTS.

The Schedule referred to in these Letters Patent and making part of the same.

To all persons to whom these presents shall come:

Be it known that I, THOMAS SMITH, Jr., of Boston, in the county of Suffolk and State of Massachusetts, have invented certain new and useful Improvements in Tea and Coffee-pots, &c.; and that the following is a full and exact description of the same, reference being had to the accompanying plate of drawings.

The principal object of the present invention is to overcome the objections to the use of Britannia metal incident to its liability to melt at a comparatively low degree of heat.

The invention consists in constructing the bottom of a Britannia tea and coffee-pot, with a plate of suitable form, of sheet-tin or iron, or other metal capable of bearing a high degree of heat without injury, by attaching such sheet-tin or iron directly to and over the outside surface of the ordinary Britannia bottom, through soldering or otherwise, and thus making said sheet-tin or iron the contact surface with the stove, in combination with providing said sheet-iron or tin plate with one or more holes through its thickness, so that in case of any leak to the pot between the Britannia and tin-bottom plates, the steam generated between them can have free exit and escape.

In the accompanying plate of drawings my improvements in tea and coffee-pots are illustrated.

Figure 1 being a partial side elevation of a teapot constructed according thereto, but with the bottom plates in transverse vertical section.

Figure 2 is a plan view of the bottom.

Figure 3, a detail view hereinafter referred to.

A in the drawing represents a teapot made of Britannia metal, of which

B is the handle;

C the lid; and

D, the spout.

E is the bottom plate of teapot A, which plate is made of Britannia metal, spun up into any suitable shape or form.

F, a plate or sheet of tin or iron applied to the Bri-

annia bottom plate E, upon the outside surface thereof, forming a covering to the same, where it is secured by soldering it along and around its edge *a* to the Britannia plate.

With a sheet-tin or iron bottom plate applied to the ordinary Britannia bottom of a Britannia tea or coffee-pot, as has been hereinabove described, the Britannia bottom and pot itself will not melt at a low degree of heat, but is rendered susceptible of resisting as great a degree as if made of sheet-tin or iron, or of a metal equivalent thereto, the advantages of which are obvious.

b, an aperture made in the center of the sheet-tin bottom plate F, through which, should there be any leak through the Britannia bottom of the pot, the steam that would consequently become generated in and between the two bottom plates can escape and pass off, thus avoiding all possibility of an explosion, which would be liable to occur were the steam allowed to be confined therein and no escape for it provided.

In lieu of one aperture *b* more may be provided, but one is deemed sufficient; and, furthermore, in lieu of the mode described and shown, in which the sheet-tin or iron bottom plate is applied to the Britannia bottom, it may be attached in the manner shown in fig. 3, or in various other modes as may be deemed best to serve the purposes of its use.

The sheet-tin bottom F may lie in direct contact with the Britannia bottom E in lieu of, as shown in the drawings, with a space between.

Having thus described my invention, I shall state my claim as follows:

The aperture *b* in bottom plate F, substantially as and for the purpose described.

The above specification of my improvements in tea and coffee-pots, &c., signed by me this 29th day of October, A. D. 1869.

THOS. SMITH, Jr.
